CLAIM

The ornamental design for a portable two-way radio stand, as shown and described.

DESCRIPTION

FIG. 1 is a perspective view of a portable two-way radio stand embodying my new design, and showing the front, top, and left side thereof;

FIG. 2 is a right side elevational view thereof;

FIG. 3 is a rear elevational view thereof;

FIG. 4 is a bottom plan view thereof; and,

FIG. 5 is a view taken along the line 5—5 in FIG. 2.
